UNITED STATES PATENT OFFICE.

CHARLES LORD, OF MINERSVILLE, PENNSYLVANIA.

DRILL.

1,062,486.

Specification of Letters Patent.

Patented May 20, 1913.

Application filed January 3, 1913. Serial No. 740,042.

To all whom it may concern:

Be it known that I, CHARLES LORD, a citizen of the United States, residing at Minersville, in the county of Schuylkill and State of Pennsylvania, have invented new and useful Improvements in Drills, of which the following is a specification.

This invention relates to miners' tools; and has for its object the provision of a 10 drill wherein will be included separable shank and cutting portions and means for strengthening the portions at the joint between their points of connection and for positively preventing the separation of the 15 cutting portion from the shank during the cutting operation.

With this and other objects in view, the invention consists of certain novel features of construction, combination and arrangement of parts, as will be hereinafter described and claimed.

In the accompanying drawings:—Figure 1 is a perspective view of the tool, showing the parts assembled. Fig. 2 is a vertical 25 longitudinal section therethrough; and Fig. 3 is a section on line 3—3 of Fig. 2.

The tool comprises separable shank and cutting portions 1 and 2, respectively, which are each of the same transverse diameter 30 whereby the tool may be driven into the material to any portion of the length of the tool, as is evident. The section or cutting portion 2 is provided through its axial center with a rectangular, relatively short 35 socket 3, which is adapted to receive a correspondingly formed tang 4 on the attaching end of the shank 1. The rectangular configuration of the tang 4 is preferable, in that the flat sides of the tang will lie in 40 mutual contact with the flat walls of the socket so as to resist any tendency of the companion portions 1 and 2 to rotate relatively when striking pressure is brought upon the tool.

45 The shank 1 is provided at diametrically opposite points with grooves 5, which are adapted to register or to aline with similar grooves 6 in diametrically opposite sides of the cutting portion 2 and to receive there- 50 with coupling and reinforcing plates 7. The ends of the plates are beveled, as at 8, so as to snugly underlie the under-cut end walls 9 of the recesses 5 and 6, so that the plates are held against lateral displacement when 55 the sections 1 and 2 are coupled. This construction is also such that both plates may be

operatively retained upon the tool through the provision of a single fastening screw 10. This screw has an outer portion or head lying flush with the outer surface of one of the plates, while the shank of the screw is extended through an aperture 11 in the cutting portion 2 and then threadedly fitted in a short bore 12 in the tang 4.

Now that the details of construction of the 65 tool are clearly described, it is said that on the initial connection of the companion portions 1 and 2, the tang 4 is extended part way into the receiving socket 3 of the portion 2. The reinforcing plates 7 are then 70 associated with the tool at diametrically opposite points thereon and arranged so as to span the joint between the portions 1 and 2 and to lie in their receiving recesses 5 and 6. The portions 1 and 2 are then moved longitudinally toward each other so as to cause the beveled ends 8 of the reinforcing plates to properly underlie the hereinbefore described undercut walls 9 of said recesses. Now the fastening screw 10 is extended 80 through one of the plates and through the aperture 12 and then operatively fitted in the bore 12 of the connecting tang 4. Both tool portions 1 and 2 are then 85 held properly connected with each other; 90 the joint between the tool portions is strengthened and the tool portions are securely held against relative rotation. The user of the tool may supply himself with any desired number of cutting portions 2 so 95 that a worn or broken portion may be quickly removed and a new one substituted therefor at a minimum cost and with the maximum saving of time and labor. It is stated that the rectangular shape of the 100 tongue 4 is desirable in that the tool sections will be held against rotation on the initial connection of said portions and as a consequence alinement of the grooves 5 with the groove 6 will be insured.

Having thus described my invention, what I claim is:—

1. A drill comprising a cutting portion and a striking shank portion, the cutting portion having longitudinally extending 105 grooves therein at diametrically opposite points, the shank portion having longitudinal grooves therein at diametrically opposite points, the grooves of the shank alining with the grooves of the cutting portion, 110 the first and second named grooves having undercut walls, plates lying within the

grooves and having beveled extremities underlying the undercut walls whereby the plates are held against lateral displacement, and a single fastening device extending 5 through one of the plates and removably fitted with the shank portion and the cut portion.

2. A drill comprising a cutting portion and a shank portion, the cutting portion 10 having a rectangular socket therein, the shank portion having a rectangular tang extending into the socket, the cutting portion having grooves therein at diametrically opposite sides, the shank having grooves

therein at diametrically opposite sides 15 adapted to register with each other when the tang is extended into the socket, means for holding the plates against lateral displacement, and a fastening device extending through one of the plates and through the 20 cutting portion and removably fitted in the tang.

In testimony whereof I affix my signature in presence of two witnesses.

CHARLES LORD.
